UNITED STATES PATENT OFFICE.

EVALENA S. THOMAS, OF LINDENWOLD, NEW JERSEY.

DESIGN FOR A TILE.

SPECIFICATION forming part of Design No. 31,450, dated August 22, 1899.

Application filed December 29, 1898. Serial No. 700,668. Term of patent 7 years.

To all whom it may concern:

Be it known that I, EVALENA S. THOMAS, a citizen of the United States, residing at Lindenwold, Camden county, State of New Jersey, have invented and produced a certain new and original Design for Tiles, of which the following is a full, clear, and exact description, reference being had to the accompanying drawings, forming a part of this specification.

10 My invention relates to the external form or configuration of tiling employed in laying mosaic or other tiled surfaces; and it consists in the novel shape or configuration of such tiles, the distinguishing characteristics of which are shown in the annexed drawings, in

15 which—
Figure 1 is an elevation of my tile-block, and Fig. 2 is a plan view thereof.
The essential and distinguishing character-

istics of my new tiling-block are its four curvilinear sides or vertical edges, two of these sides *a a* being alike and concave and meeting each other at a point, the two other sides *b b* being alike and convex and meeting each other at a point, so as to form a four-sided curvilinear figure having two equal convex sides opposite two equal concave sides.

20 I claim as new—

The design for a tile, substantially as shown and described.

25 In testimony whereof I have hereunto affixed my signature this 19th day of December, A. D. 1898.

EVALENA S. THOMAS.
